UNITED STATES PATENT OFFICE

PHILIP KEMPTER, OF MILWAUKEE, WISCONSIN, ASSIGNOR TO GENDER, PAESCHKE & FREY COMPANY, OF MILWAUKEE, WISCONSIN, A CORPORATION OF WISCONSIN

DESIGN FOR A COMBINATION BREAD AND CAKE COVER

Application filed August 18, 1930. Serial No. 36,695. Term of patent 3½ years.

To all whom it may concern:

Be it known that I, PHILIP KEMPTER, a citizen of the United States, residing at Milwaukee, in the county of Milwaukee and State of Wisconsin, have invented a new, original, and ornamental Design for Combination Bread and Cake Covers, of which the following is a specification, reference being had to the accompanying drawing, forming a part thereof, and in which the figure is a perspective view of a combination bread and cake cover showing my new design.

I claim:

The ornamental design for a combination bread and cake cover as shown.

PHILIP KEMPTER.
